US0D1098256S

(12) **United States Design Patent** (10) **Patent No.:** **US D1,098,256 S**
(45) **Date of Patent:** **** Oct. 14, 2025**

(54) **THERMAL TRANSFER PRINTER**

(71) Applicant: **VIDEOJET TECHNOLOGIES INC.**,
Wood Dale, IL (US)

(72) Inventors: **Martin McNestry**, Nottingham (GB);
Steven John Buckby, Nottingham (GB); **Ben Meyerowitz**, Nottingham (GB)

(73) Assignee: **Videojet Technologies Inc.**, Wood Dale, IL (US)

(**) Term: **15 Years**

(21) Appl. No.: **29/809,237**

(22) Filed: **Sep. 27, 2021**

(51) LOC (15) Cl. **18-99**

(52) U.S. Cl.

USPC **D18/19**

(57) **CLAIM**

The ornamental design for a thermal transfer printer, as shown and described.

DESCRIPTION

FIG. 1 is a front view of a thermal transfer printer in accordance with the present new design;

FIG. 2 is a top view of the thermal transfer printer of FIG. 1;

FIG. 3 is a left side view of the thermal transfer printer of FIG. 1;

FIG. 4 is a right side view of the thermal transfer printer of FIG. 1;

FIG. 5 is a bottom view of the thermal transfer printer of FIG. 1;

FIG. 6 is a rear view of the thermal transfer printer of FIG. 1;

FIG. 7 is a bottom front perspective view of the thermal transfer printer of FIG. 1;

FIG. 8 is a top front perspective view of the thermal transfer printer of FIG. 1; and,

FIG. 9 is a rear perspective view of the thermal transfer printer of FIG. 1.

The broken lines immediately adjacent to the shaded areas and define unshaded broken line regions depict the bounds of the claimed design, while all other broken lines are directed to environment. The broken lines form no part of the claimed design.

1 Claim, 9 Drawing Sheets
